UNITED STATES PATENT OFFICE

118,588

DESIGN FOR AN ELECTRICAL WIRE CONNECTOR

Jasper Blackburn, Webster Groves, Mo.

Application February 11, 1939, Serial No. 82,923

Term of patent 3½ years

To all whom it may concern:

Be it known that I, Jasper Blackburn, a citizen of the United States, residing at Webster Groves, in the county of St. Louis and State of Missouri, have invented a new, original, and ornamental Design for Electrical Wire Connectors, of which the following is a specification, reference being had to the accompanying drawing, forming part thereof.

Figure 1 is a side elevation of the electric wire connector showing same closed.

Figure 2 is a side elevation of the connector showing same partially open.

Figure 3 is a top plan view of the connector.

Figure 4 is a front end view of the connector.

I claim:

The ornamental design for an electrical wire connector, as shown.

JASPER BLACKBURN.
